Stephen J. Winchester of Boston, Mass.

Assigns to

E. A. & W. Winchester, of the same place.

Letter Patent No. 2030 Dated Feb. 7, 1865.

Design for a trade mark.

The schedule referred to in the letter Patent and making part of the same.

In all respects to whom these Presents shall come,

Be it known that of Stephen J. Winchester, of Boston, in the County of Suffolk and State of Massachusetts, has invented a design for a Trade Mark, for use on Packages of soap, and I, hereby declare the same to be described in the following specification and represented in the accompanying drawing.

The trade mark in question consists of the letter R, and the word or expression "With Soap," the whole being as represented in the accompanying drawing.

I claim the design for a trade mark substantially and described and represented.

Witness,

R. H. Eddy,

S. J. Winchester
